UNITED STATES PATENT OFFICE.

ROBERT M. KINNARD, OF SEBRING, OHIO.

STOVE-ROOM FOR POTTERIES.

1,249,772.

Specification of Letters Patent.

Patented Dec. 11, 1917.

Application filed June 16, 1917. Serial No. 175,239.

To all whom it may concern:

Be it known that I, ROBERT M. KINNARD, a citizen of the United States, residing at Sebring, in the county of Mahoning and 5 State of Ohio, have invented a new and useful Stove-Room for Potteries, of which the following is a specification.

My invention relates to drying racks and has more especial reference to what is known 10 as a "stove room", being a series of drying shelves which is used in potteries for drying the ware after the same has been molded and previous to burning the same.

In the ordinary forms of "stove rooms", such as are at present in use in potteries the 15 drying racks are generally stationary within an inclosed room, aisles being left between each tier of shelves to permit the workmen to pass between the racks or frames when 20 placing the green articles from the molds upon said shelves or in removing the dried articles therefrom. A series of steam pipes are located upon the floor of the "stove room" maintaining an even temperature of 25 from 110° to 120° F. within the "stove room" constantly. With this form of "stove room" it is necessary in filling or emptying the frame for the men to work in the "stove room" and the extremely high temperature 30 of the room makes it impossible for a man to stay on the job longer than an hour at a time. In constructing the above described form of stove room it is necessary to space each rack of shelves sufficiently from the ad- 35 jacent racks to allow the men to pass through the aisles between the racks and this construction necessitates the utilization of considerable floor space.

The object of my invention is to provide a 40 stove room which comprises sufficient shelf space to hold an entire day's output of one workman, considerably less floor space being used than in the present form of stove room.

A further object is to provide a "stove 45 room" of the character mentioned upon which the ware may be thoroughly dried without necessitating the use of a series of steam pipes or their equivalents beneath the drier racks.

50 A still further object is the provision of a stove room of the character referred to in which the temperature of the room is kept slightly above normal, but moderate enough to allow the men to work therein without any great hardship.

55 A still further object is to provide a stove

room of the character mentioned in which it is not necessary to inclose the drying racks in a separate room from the room in which the molding is done.

60 A still further object is the provision of a shelving for stove rooms in which the shelves are formed in independently movable units arranged to be moved into positions to permit of their being filled or emptied with a 65 minimum amount of labor.

A still further object is the provision of shelving of the character mentioned in which the shelves are formed in two parallel rows of units or racks, the racks in one row being moved longitudinally across the device 70 while the racks in the other row are movable both longitudinally and transversely.

75 My improved form of stove room comprises a drying device arranged to be located within the room in which the molding is done. With this construction no steam pipes are used beneath the drying racks as in the form of stove rooms at present in use, it being merely necessary to maintain the 80 temperature of the room in which the device is located slightly above normal, the temperature being sufficiently moderate to allow the men to work in the room without putting any hardship upon them. My con- 85 struction comprises stationary end sections which are provided with shelves, a series of tracks connecting said end sections at their upper extremities. A series of movable sections are slidably mounted upon said tracks 90 by means of pulleys, each of said movable sections being provided with a series of shelves of sufficient width to receive two molds. A second series of movable sections is slidably mounted upon beams which are 95 mounted upon said tracks by means of pulleys. The device is so constructed that the movable sections may be moved in such a position to allow the men to pass before the 100 racks being filled or emptied, the device being so constructed that when all the shelves are filled the movable sections may be spaced from each other and from the stationary end sections sufficiently to allow a complete circulation of air around said sections. The 105 entire device, constructed as above briefly pointed out may be placed within consider- 110 ably less floor space than is required for the present form of stove rooms and is so constructed that the labor of filling or empty- ing the shelves is reduced about one-half.

It is preferable to construct each of the de-

5 vices of proper dimensions to hold an entire day's output of one man and the ware is sufficiently dried over night to be removed in the morning, allowing the shelves to be refilled each day.

With these objects in view the invention consists in the novel construction and arrangement of parts, hereinafter described, illustrated in the accompanying drawings, 10 and particularly pointed out in the appended claims, it being understood that various changes in the form, proportions, size, and minor details of construction may be made within the scope of the appended claims, 15 without departing from the spirit or sacrificing any of the advantages of the invention.

In the drawings:

Figure 1 is a top plan view of the device showing the movable sections placed in the 20 position best adapted to facilitate the drying of the ware.

Fig. 2 is a section on the line 2—2, Fig. 1.

Fig. 3 is an end view of the device showing the racks in the positions shown in Fig. 1.

25 Fig. 4 is an end view of the device showing the movable sections in position to allow a workman to fill or empty one of the stationary end sections and the near side of the adjacent movable section.

30 Similar numerals of reference indicate corresponding parts throughout the several figures of the drawings.

Referring more especially to the construction illustrated in the accompanying drawings, the numeral 1 indicates the standards upon which the device is supported, these standards being four in number and located at the four corners of the stove room. Each end pair of the standards 1 is connected at 35 its upper extremities by means of a transversely disposed I-beam 2. A stationary rack or tier of shelves 3 of about half the width of the device, is located between each pair of standards 1 and adjacent the standards upon one side of the device thus forming a stationary rack or tier of shelves at each extremity of the device and upon the same side thereof. Suitable tracks 4 are superimposed upon the I-beams 2 and connect adjacent corners of the device, a channel shaped track member 5 being also superimposed upon said I-beams and extending through the center of the device.

40 A plurality of movable racks 6 are supported by means of the pulleys 7 upon one of the tracks 4 and the channel member 5, these racks being of the same dimensions as the stationary racks 3 and located in alinement therewith. The construction of each 45 of these movable racks is the same, each rack being preferably composed of a spaced tier of shelves 8 preferably of suitable width to receive two rows of molds. For the purpose of future reference the racks 6 are designated by the letters *a*, *b*, *c* and *d*.

Between each pair of racks 6 and between the end racks *a* and *d* and the adjacent stationary racks 3 is mounted a beam 9 of channel shape in cross section, these beams being supported upon the tracks 4 by means of 50 pulleys 10 and upon the channel 5 by means of pulleys 11. Upon each of the beams 9 is slidably supported, by means of pulleys 12, a rack 13, each of these racks being of substantially the same size and form as the 55 racks 6, and provided with suitable shelves 14. It will thus be seen that each of the racks 13 may be slidably moved upon its beam 9 either into the position best shown in Fig. 1 or to the end of the beam where the 60 rack will be in alinement with the racks 6.

When it is desired to fill the device the racks *a*, *b*, *c* and *d* are moved together as shown in Fig. 4 of the drawings and the rack 13 designated by the numeral *e* is moved 65 upon its beam 9 to a point where it is in alinement with the racks 6 after which the beam 9 carrying the rack *e* is moved back bringing said rack *e* adjacent the rack *a*, the other beams 9 carrying the racks designated by the letters *f*, *g*, *h* and *i* being moved toward the rear side of the device bringing said racks into juxtaposition with each other. An aisle is thus left between the rack *e* and the adjacent stationary rack 3 through 70 which aisle the workmen may pass in filling or emptying the shelves within said rack. After one side of the rack *e* has been filled, said rack is moved forwardly against the adjacent rack 3 thus leaving an aisle between the rack *e* and the rack *a*. The other side of the rack *e* together with the adjacent side of the rack *a* is then filled after which the rack *e* is moved upon its beam 9 back into the position shown in Fig. 1 and the rack *f* 75 is moved upon its beam into alinement with the rack 6 and backwardly against the rack *b*, adjacent sides of the racks *a* and *f* being then filled. This operation is continued, each of the racks 13 being moved into alinement with the racks 6 and then back to the 80 position shown in Fig. 1, all of the racks being separated as shown in Figs. 1 and 3 after they have been entirely filled thus allowing a circulation of air entirely around 85 all of the racks for the purpose of drying the ware.

Each of the stove rooms as above described 90 comprises sufficient shelf space to accommodate an entire day's output of one molder and the ware dries sufficiently over night to be removed in the morning, allowing the racks to be refilled each day as the articles are molded.

95 It will be seen from the above description and inspection of the accompanying drawings that this device is compact, using the very least possible amount of space within which the ware can be placed for drying and that with the double arrangement of the 100

racks a great many steps are saved by the workmen in emptying or filling the racks as it is only necessary for the workmen to walk half the width of the device in filling each rack since the racks are moved into alinement as they are filled or emptied after which the double movable racks 15 are moved back to the position shown in Fig. 1.

I claim:

10. 1. A device of the character described, comprising stationary spaced end racks and movable racks mounted between said end racks and arranged to be moved independently toward and from said stationary racks and transversely out of alinement with said stationary racks.

20. 2. A device of the character described, comprising stationary spaced end racks, tracks connecting said end racks, a plurality of movable racks mounted upon said racks and arranged to be moved independently toward and from said stationary racks, a plurality of beams mounted upon said tracks and arranged to be moved independently toward and from said stationary racks and a movable rack mounted upon each of said beams and arranged to be moved into alinement toward and from said stationary racks and a rack movably mounted upon each of said beams and arranged to be moved thereon.

30. 3. A device of the character described, comprising spaced stationary end racks,

tracks connecting said end racks, a second set of tracks parallel to said first mentioned tracks and located at one side of said end racks, a plurality of movable racks mounted upon said first mentioned tracks and arranged to be moved independently toward and from said stationary racks, transversely disposed beams mounted upon said second mentioned tracks and upon one of said first mentioned tracks, said beams located between adjacent pairs of said movable and stationary racks, and a rack slidably mounted upon each of said beams.

40. 4. A device of the character described comprising stationary end racks, a plurality of movable racks mounted between said end racks and arranged to be moved independently toward and from said end racks, a transversely disposed movable beam mounted between each pair of said racks and arranged to be moved independently toward and from said stationary racks and a movable rack mounted upon each of said beams and arranged to be moved into alinement with said first mentioned racks or out of alinement therewith.

In testimony that I claim the above, I have hereunto subscribed my name.

ROBERT M. KINNARD.
